(57) **CLAIM**

The ornamental design for the foldable computer mouse, as shown and described.

DESCRIPTION

FIG. 1 is a perspective view of the foldable computer mouse in the folded configuration;

FIG. 2 is a front elevational view of the foldable computer mouse in the folded configuration;

FIG. 3 is a side elevational view of the foldable computer mouse in the folded configuration;

FIG. 4 is a top plan view of the foldable computer mouse in the folded configuration;

FIG. 5 is a rear elevational view of the foldable computer mouse in the folded configuration;

FIG. 6 is a top plan view of the foldable computer mouse in the unfolded configuration;

FIG. 7 is a side elevational view of the foldable computer mouse in the unfolded configuration; and,

FIG. 8 is a bottom plan view of the foldable computer mouse in the unfolded configuration.
